SECTIONAL DOOR MECHANISM

Charles C. Gill, Richard O. Julian, John W. McIlwraith, and Charles F. Rutledge, Elwood, Ind., assignors of one-half to John W. McIlwraith and one-half to Charles F. Rutledge, both of Elwood, Ind.

Application July 29, 1932, Serial No. 625,791

8 Claims. (Cl. 20—20)

This invention relates to a sectional door construction.

The chief object of this invention is to provide sectional doors with certain improvements, whereby said doors are commercially more acceptable than those heretofore utilized.

While the invention is disclosed herein as applied to folding sectional doors, certain features thereof apply equally as well to sliding sectional doors and unless otherwise specified in the claims, the terminology "sectional door" is intended to cover both the sliding and the folding types.

One feature of the invention consists in the sealing means interposed between the side jamb and the door section.

A second feature of the invention consists in the sealing means interposed between the top jamb and the top door section.

A third feature of the invention consists in the nested handle applied to folding sectional doors, wherein the handle is nestable between adjacent door sections when folded and the gripping portion is sufficiently remote from the supporting door section when unfolded, so that the hand of the operator may conveniently be interposed between the door section and the gripping portion.

Another feature of the invention consists in the combination bolt and lock employed for securing the sectional door in closed position and it furthermore is arranged for manual operation from either side of the bolt supporting member (usually the door section) when the lock is unlocked or moved to bolt releasing position.

The full nature of the invention will be understood from the accompanying drawings and the following description and claims:—

In the drawings, Fig. 1 is a rear elevation of one end of a sectional door in closed position and the adjacent side jamb of the door opening.

Fig. 2 is an enlarged transverse sectional view taken on line 2—2 of Fig. 1, and in the direction of the arrows.

Fig. 3 is a view similar to Fig. 1 and of a modified form of the invention.

Fig. 4 is a transverse sectional view taken on line 4—4 of Fig. 3, and in the direction of the arrows.

Fig. 5 is a vertical sectional view through the top jamb of a door opening and the top section of a folding sectional door in which the door section moves upwardly and in certain instances forwardly.

Fig. 6 is a similar view of a modified form of the invention shown in Fig. 5.

Fig. 7 is a vertical sectional view through a

sectional door in overhead folded relation embodying a handle nested between the door sections, the dotted lines indicating the door sections in open position.

Fig. 8 is an enlarged sectional view similar to Fig. 7 showing the handle in nested relation and the mounting thereof between adjacent door sections.

Fig. 9 is a rear view of a portion of a side jamb and a door section mounting a socket and bolt respectively, with which is associated a lock control.

Fig. 10 is an enlarged transverse sectional view through the same.

Fig. 11 is a front view of the lock and handle associated therewith.

Fig. 12 is a rear elevation of a modified form of bolt and lock control.

Fig. 13 is a vertical sectional view through the bolt supporting member and the mechanism associated with the bolt.

Fig. 14 is a front elevation of the exposed handle or lock.

Fig. 15 is a rear elevation of one end of a sectional door in closed position, the adjacent side jamb and a modified form of side sealing means.

Fig. 16 is a similar view showing the door in open position.

Fig. 17 is a top plan view of the door section, side jamb and sealing means.

Fig. 18 is a side elevation of the parts shown in Fig. 17.

In Figs. 1 and 2 of the drawings, 10 indicates a side jamb, 11, 12, 13 and 14 indicate respectively four superposed, and in the present form of the invention, hingedly connected door sections. Mounted on the side jamb is a sealing strip 15 which is hingedly supported thereby as at 16. If the hinge means 16 is not of a spring constrained type, an additional spring means 17 is anchored as at 18 at one end to the door jamb and at 19 to the sealing strip 15. The sealing strip 15 is reduced as shown clearly at Fig. 2. Supported by the section 12 is a laterally projecting strap 20 with a forwardly directed arm 21. Said forwardly directed arm 21 is adapted to engage the inclined surface 22 of a cam secured as at 23 to the sealing strip.

In the lowering movement of the door and just prior to the movement of the section into final door closing position, the arm 21 engages the cam 22 and tilts the sealing strip 15 in opposition to its constraint, whether the same be included in the hinges 16 or imposed by means of spring 17.

55

In Figs. 3 and 4, a modified form of the invention is illustrated. In this form of the invention similar parts are indicated by numerals of the one hundred series. The side jamb 110 is operatively associated in the same manner with the door sections 111, 112, 113 and 114 as heretofore. A sealing means consists of a plurality of strips 115a and 115b. These are hingedly connected together as at 115c. Door section 112 supports the strap 120 having the actuating arm 121 which engages the cam 122 anchored at 123 for straightening out or causing the plurality of hingedly connected sealing strip sections to move into alignment and in so moving into alignment, said strip sections move into engagement with the ends of the door sections, as shown in Fig. 4. The strip sections are pivotally supported on the jamb and in a sense hingedly supported thereby as at 116a and the free end thereof and herein the upper end is slidably supported in a socket 116b. When the door sections move to final closing position, the arm 121 engages the cam 122 and aligns all the sealing sections and in such alignment the ends of the door sections are sealed to the side jamb.

In Fig. 5 there is illustrated one form of top seal construction. Herein the top jamb is indicated by the numeral 230 and the top section by the numeral 214. The top section may support a roller, guide or shoe 231 which moves upwardly in the slot or track 232 which, in the present form of the invention, is shown provided with a forwardly directed end 233. The aforesaid construction is clearly illustrated in the co-pending application of Charles F. Rutledge, filed November 28, 1930, and bearing Serial No. 498,698, now Patent No. 1,962,913, June 12, 1934, and is also disclosed in the co-pending application of Gill, et al., Serial No. 614,894, filed June 2, 1932 by the aforesaid and others, now Patent No. 2,020,544, Nov. 12, 1935.

The top of the top door section upon its forward face includes a sealing strip 234. Supported by the top jamb is a rearwardly directed angle iron sealing strip 235, the rearwardly directed flange thereof lying in a plane below the sealing strip 234. When the door arrives at its final closed position, sealing strip 234 engages the rearwardly directed flange or sealing member 235 and seals the top of the door to the top jamb.

In Fig. 6 a modified form of the invention is illustrated in which numerals of the two hundred series are employed. The operation is substantially the same.

In Figs. 7 and 8 there is illustrated the handle mounting and in this form of the invention, the door is of the folding sectional type. The door sections are indicated by numerals of the four hundred series. Thus, 411 indicates the lowest section, 412 the second lower section, 413 the second upper section and 414 the top section. These are hingedly connected together as shown as at 410.

Suitably secured to the top rail 412a of the second section 412 having the panel 412b, is a U-shaped handle having flat free ends 440 secured as at 441 to the rail 412. The handle adjacent the panel has a channel formation as indicated as at 442 and the intermediate portion between the two arms 442 is arranged in semi-circular section and semi-cylindrical formation as at 443. As shown clearly in Fig. 8, this handle portion terminates adjacent the panel 411b of

door section 411, the bottom rail 411a thereof lying substantially in abutting relation to the portion 440 of the handle. Usually two handles in horizontal alignment are employed.

In Figs. 9 to 11 inclusive, there is illustrated a form of locking device and in said figures, 511 indicates a side jamb member, 511 a door section member. A U-shaped bracket 550 is secured to the door member 511 and slidably supported in the ears 551 thereof is a bolt 552 which is receivable by the socket 553 carried by the side jamb adjacent the opening and is secured to said side jamb as at 554. A spring 555 is connected as at 556 to the bolt 552 at one end and its opposite end is connected as at 557 to the remote ear 551. A rock shaft 558 extends through the door member and upon the front end of said shaft is secured an arm 559 terminating in a finger piece 560. The inner end of the shaft 558 supports a link 561 that is pivotally connected to another link 562 at 563. The other end of the link 562 is pivotally connected as at 564 to the free or rear end of the bolt 552. The pivotal connection 563 also supports a finger piece 565 on the inside of the door. Thus, the bolt may be manually reciprocated by either the finger piece 560 from outside the door or by the finger piece 565 from within the door.

The arm 561 includes a recess 566 and a pin or equivalent member 567 is carried by a lock 568 and said pin normally seats in the aperture 566 when the lock is in locked position. When the lock is in unlocked position, the pin 567 is retracted and then the door may be opened from either the inside or the outside by respectively actuating the inside or outside finger pieces. The pin 567 may be of the type that is normally projected into locking relation and when thus projected, the bolt can only be withdrawn from the inside of the door by depressing the pin 567 in opposition to its usual constraint and at the same time moving the bolt mechanism so that the arm 561 is moved sufficiently for non-registration of the recess 566 and the pin 567.

The arm 561 includes a lateral enlargement 569 which prevents the pin from projecting outwardly into locking position when the arm 561 has been moved into the bolt withdrawal position, so that the lock will not prevent the manual return of the bolt when desired and thus this arrangement does not require unlocking of the lock for the seating of the bolt in its socket.

In Figs. 12 to 14 inclusive, there is illustrated a slightly different and modified form of the aforesaid locking and bolt construction, and numerals of the six hundred series are employed for like or similar parts.

Herein the plate 650 is suitably secured to the door member 611. The plate includes a pair of spaced ears 651 which slidably support bolt 652. One end of the bolt as at 664 is pivoted to an arm or link 662 in turn pivoted at 663 to a lever arm 661, in turn pivoted at 658. A shaft forming the pivot 658 projects through the door and upon its outer and exposed end mounts a lever 659 terminating in a handle portion 660. When the handle is turned, the rock shaft 658 turns and with it turns lever arm 661 providing the locking mechanism is released permitting such movement. The lever arm 661, as stated, is pivotally connected at 663 to the link 662 connected to the locking bolt 652 at 664.

To insure bolt projection in locking position, a coil spring 655 is employed which is coiled about the pivot 663 and has one end anchored as at 657

to the lever arm 661 and the other end anchored as at 656 to the link 662; thus constraining the two members toward each other which constrains the locking bolt toward locking position, 5 and in this respect, this form of the invention differs from the form shown in Figs. 9 to 11 inclusive.

If desired, the pivotal connection 663 may support a finger piece 665 upon the inside of the 10 door. Mounted in the door and projecting therethrough, is a lock cylinder 668 which has a pin 667 which registers with an opening formed in the supporting plate 650 and in this respect is similar to the form of the invention shown in 15 Figs. 9 to 11 inclusive. The bolt also is adapted to register with a recess 666 in the lever arm 661. The lever arm 661 carries a U-shaped bracket 670 having a pair of aligned openings 671 therein which are in alignment with opening 20 666.

The aforesaid serves as a support for a releasing member 672 having the finger engageable portion 673. The purpose of this portion is to press toward the lock the outwardly constrained pin 667 and when thus depressed, the lever may be manually moved through the finger piece 665, since the lever is released from the pin lock. When the bolt is to be actuated from above the door, the lock is actuated to retract 30 the pin 667 and then the finger piece 660 is actuated to withdraw locking bolt 652 into retracted position.

In Figs. 15 to 18, inclusive, is illustrated a modified form of the invention. As shown in 35 Figs. 5 and 6, the guide or trackway has a forwardly directed curvature or socket and the upper roller 731 in its upward movement also moves forwardly toward the jamb 710. The door sections 711, 712, 713 and 714 are connected together as aforesaid. The side jamb supports a rail 770 supporting a plurality of plate guides 771. Rail 770 has one edge 772 inclined upwardly and away from the door opening. Another rail 773 is positioned adjacent the door opening 40 and may have its remote edge 774 directed upwardly and toward the door opening if desired but it is herein shown parallel thereto. A sealing member 775 has complementary opposite sides for wedging association when the door is 45 fully closed. It also supports an angle iron 775^a that seats in groove 776 in the ends of the door sections.

A U-shaped strap 777 of relatively elongated formation, see Fig. 18, straddles the pintle 778 supporting upper guide wheel 731. Strap 777 is carried by sealing member 775 so that as the wheel and door move, the sealing member moves vertically therewith and laterally along the pintle 778 as the sealing member moves laterally 50 into engagement with rail 773 and away from the same. When sealing, the iron 775^a also engages the side edges of the ends of the door sections.

The invention claimed is:—

1. In a sectional door, the combination of a plurality of hingedly and horizontally connected foldable door sections arranged to fold overhead for door opening and for movement downwardly for door closing, a side jamb, a stationary guide track adjacent thereto, guide means on the door movable therein, a sealing means supported by the jamb and constrained toward non-sealing position, a member on the door and movable therewith, and means on the sealing means engageable by the member in door closing move- 5

ment substantially when finally closing for causing said sealing means to seal the door to the jamb.

2. In a sectional door, the combination of a plurality of hingedly and horizontally connected foldable door sections arranged to fold overhead for door opening and for movement downwardly for door closing, a side jamb, a stationary guide track adjacent thereto, guide means on the door movable therein, a sealing means supported by the jamb, a member on the door and movable therewith, means on the sealing means engageable by the member in door closing movement substantially when finally closing for causing said sealing means to seal the door to the jamb, and means hingedly mounting the sealing means on the door jamb, the member tilting the sealing means into door section end engagement. 10 15

3. In a sectional door, the combination of a plurality of hingedly and horizontally connected foldable door sections arranged to fold overhead for door opening and for movement downwardly for door closing, a side jamb, a stationary guide track adjacent thereto, guide means on the door movable therein, a sealing means supported by the jamb, a member on the door and movable therewith, and means on the sealing means engageable by the member in door closing movement substantially when finally closing for causing said sealing means to seal the door to the jamb, said sealing means comprising a plurality of hingedly connected strips arranged upon actuation by the member to assume an aligned and sealing position. 20 25 30 35

4. In a sectional door in which the upper edge of the upper door section moves upwardly and forwardly, the combination of a top jamb, a sealing member carried thereby and extending toward the door, and another and cooperating sealing member carried by the upper door section and movable upwardly therewith in door opening and positioned above the first mentioned member and extending toward the jamb. 40

5. In a sectional door in which the upper edge of the upper door section moves upwardly, the combination of a top jamb, a sealing member carried thereby and extending toward the door, and another and cooperating sealing member carried by the upper door section and movable upwardly therewith in door opening and positioned above the first mentioned member and extending toward the jamb. 45 50

6. In a sectional door, the combination of a plurality of hingedly and horizontally connected foldable door sections arranged to fold overhead for door opening and for movement downwardly for door closing, a side jamb, a stationary guide track adjacent thereto, guide means on the door movable therein, sealing means guided by the jamb, and a member on the door operatively associated with the sealing means for moving the same into and out of sealing position in the door closing and opening movement, said sealing means including a wedge member vertically movable by the door. 55 60 65

7. In a sectional door, the combination of a plurality of hingedly and horizontally connected foldable door sections arranged to fold overhead for door opening and for movement downwardly for door closing, a side jamb, sealing means guided thereby, and a member on the door operatively associated with the sealing means for moving the same into and out of sealing position in the door closing and opening movement, said sealing 70 75

means including a bearing member movable laterally into door engagement by the door, said sections including a groove receiving said member.

8. In a sectional door, the combination of a plurality of hingedly and horizontally connected foldable door sections arranged to fold overhead for door opening and for movement downwardly for door closing, a side jamb, sealing means guided thereby, a member on the door operatively associated with the sealing means for moving the

same into and out of sealing position in the door closing and opening movement, said sealing means including a wedge member, and a bearing member both simultaneously movable by the door vertically and laterally for sealing, said sections including a groove receiving said bearing member.

CHARLES C. GILL.
